CUFF HOLDER

George D. Tye, New York, N. Y.

Application March 4, 1947, Serial No. 732,325

2 Claims. (Cl. 2—123)

1

This invention relates to cuff holders, that is, devices adapted to be attached to or mounted in or on upturned cuffs of shirt sleeves to prevent undoing of the cuff, and it is one object of this invention to provide a simple and effective cuff holder or retainer which is adapted to be mounted between the sleeve and the upturned cuff to hold the cuff in upturned position and thus prevent its inadvertently being turned down to the annoyance of the wearer.

Another object of the invention is the provision of a device comprising an arcuate base which is adapted to register in the lap of the fold of an upturned cuff, the base having at each end substantially vertical gripping or piercing members adapted to engage both the cuff and the shirt sleeve and thus hold the two together and prevent the cuff from turning down.

The above as well as additional objects will become apparent in the following description, wherein characters of reference refer to like-numbered parts in the accompanying drawing. It is to be noted that the drawing is intended to serve the purpose of illustration only, and that it is neither intended nor desired to limit the invention necessarily to any or all of the exact details of construction shown excepting insofar as they may be deemed essential to the invention.

Referring briefly to the drawing,

Fig. 1 is a perspective view, with parts broken away and partly in section, showing a shirt sleeve having the cuff turned up and the invention applied thereto.

Fig. 2 is a sectional view taken on the line 2—2 of Fig. 1.

Fig. 3 is a front elevational view of the cuff holder per se.

Fig. 4 is a sectional view taken on the line 4—4 of Fig. 3.

Fig. 5 is a sectional view taken on the line 5—5 of Fig. 3.

Fig. 6 is a sectional view taken on the line 6—6 of Fig. 3.

Referring in detail to the drawing, the numeral 10 indicates a shirt sleeve having the cuff 11 thereof turned up as shown in Fig. 1. The cuff holder comprises an arcuate base 12 which may be approximately semi-circular in outline and of a diameter suitable to permit insertion thereof down into the lap or bight 13 of the fold of the cuff.

Extending upward at right angles to the plane of the base 12 at the extremities of the latter are two similar rods 14 whose extremities 15 extend arcuately outward and are pointed in the manner of a pin, substantially as shown. Secured to the rods 14, one to each and radially inward therefrom, are longer rods 16. Any suitable means may be provided for securing the rods 16 to the rods 14, such as, for instance, solder. The

2

rods 16 extend higher than the rods 14 and are also arched and pointed at their upper extremities, but in opposite directions to the rods 14, that is, inwardly, as shown at 17. A limit stop collar 18 is provided intermediate the arched and pointed extremity of each rod 14 and 16.

In use, the holder is applied to the sleeve and cuff by setting the base 12 in the fold 13 so that it rests upon the floor of the fold, as shown in Fig. 1. Then the pointed extremities 15 of the rods 16 pierce the sleeve 10 and the pointed extremities 15 of the rods 14 pierce the cuff 11, or the cuff 11 is forced down upon the pointed extremities 15. The collars 18 serve as limit stops to prevent the pointed extremities from passing too far through the cuff or sleeve.

Thus, the cuff is held securely against the sleeve and it is prevented from turning down inadvertently. The desirability of and the common practice of turning the cuffs up is well known.

Obviously, modifications in form and structure may be made without departing from the spirit and scope of the invention.

I claim:

1. A device adapted to retain the cuff of a sleeve in turned up position comprising an arcuate base adapted to register in the fold between the sleeve and the upturned cuff, said base having a substantially upright member extending from each extremity thereof, each of said members having two oppositely disposed extensions extending from the upper portion thereof, said extensions lying in a common plane substantially at right angles to the plane through said base, said extensions being pointed.

2. A device adapted to retain a cuff of a sleeve in turned up position comprising an arcuate base adapted to register in the fold between the sleeve and the upturned cuff, said base having substantially upright rods on the extremities thereof, the upper extremities of said rods being arched outwardly and pointed, said rods having each a second rod secured thereto along the greater portion of the length thereof and of greater height than said first rods, the upper extremities of said second rods being arched inward and pointed, said pointed extremities of said first rods being adapted to pierce the cuff and said pointed extremities of said second rods being adapted to pierce the sleeve.

GEORGE D. TYE.
